TYPEWRITING MACHINE

Alfred G. F. Kurowski, Brooklyn, N. Y., assignor
to Underwood Corporation, a corporation of
Delaware

Application March 8, 1944, Serial No. 525,808

8 Claims. (Cl. 197—7)

This invention relates to typewriting machines and with regard to more specific features thereof to typewriting machines embodying automatic operating devices to effect automatic typing of verbal composition.

A typist during a day's work repeats typing of certain most common words and phrases and this demands in each instance his full attention, as a key must be struck for every character and word-space that occurs in such words and phrases.

Examples of such frequent words and phrases, hereinafter referred to as stock-expressions, are "Dear Sir:"; "Yours truly,"; "Very truly yours,"; "Sincerely yours,"; etc. In some instances a stock-expression may be a firm's name or a trademark, typed in complementary fragments by special complementary types.

It may be easily seen that automatic typing of such entire stock-expressions in response to a mere operation of single key would considerably ease the task of a typist and would also expedite his work inasmuch as automatic typing of a succession of characters can be effected at the greatest possible speed and inasmuch during such automatic typing a typist can give advance thought to the task still lying ahead.

With the above in view, it is an object of the instant invention to provide efficient, simple, and reliably operative means to type certain often-used multi-character stock-expressions automatically in response to a simple selective manipulation of control means, such as stock-expression selecting keys.

As an adjunct to the foregoing object of providing automatic stock-expression typing means, it is also an object of the invention to provide for prompt automatic restoration of said means, so as to be in readiness for promptly effective subsequent action.

A further object of the invention is to provide simple, efficient, and reliably operating devices for controlling and effecting automatic word-spacing and case-shifting operations in accordance with the requirements of the stock-expressions to be typed.

Also an object of the instant invention is to contrive simple and reliably effective means whereby following automatic typing of some of the said stock-expressions there occurs an automatic power driven return of the paper supporting carriage to a predetermined position, which position may vary in accordance with the exact extent of return to be effected in connection with a particular stock-expression to be typed.

A still other object of the invention is to pro-

vide a typewriting machine which embodies efficient provision for selective power-typing of single characters, and to combine therewith efficient and quickly responsive means to bring about automatic typing of multi-character stock-expressions at the will of the operator.

Still another object is to provide, in association with selective automatic expression typing means efficient devices whereby when one expression typing operation is in progress, no other such expression typing operation can be called into being.

Further objects and features of the invention will be apparent upon consideration of the detailed description which follows, as that description is read in the light of the accompanying drawings.

In the accompanying drawings illustrating a preferred embodiment of the invention:

20 Figure 1 is a sectional side elevation of a typewriting machine of the invention, taken substantially along line 1—1 of Figure 2;

25 Figure 1a is a fragmentary plan view, illustrating some details of a clutch controlling mechanism;

Figure 2 is a fragmentary plan view of the front portion of the typewriting machine seen in Figure 1;

30 Figures 3, 4, and 5 show in enlarged cross section, each a rotor or operator, equipped with a different set of control tappets or spurs for respectively inciting automatic typing and other operations for transcribing the stock-expressions: "Very truly yours,"; "Yours truly,"; and "Dear Sir,";

35 Figure 5a shows a rotor equipped with a case-shift control collar effective to maintain the case-shift while an entire stock-expression is being typed;

40 Figure 6 depicts power case-shifting mechanism and power word-spacing mechanism with the controlling devices therefor perspective as seen from the left front side of the machine;

45 Figure 7 shows an end-portion of one of the aforesaid rotors with a drive clutch associated therewith, the latter being shown in an open condition and in cross section longitudinally of the rotor;

50 Figure 8 is a fragmentary front perspective view looking against the inner right side of the typewriting machine and showing certain controlling devices whereby to render the machine selectively effective to type automatically any one of several multi-character stock-expressions;

55 Figure 9 is a sectional side elevation taken along

line 9—9 of Figure 2, and illustrates a portion of a selective, power driven carriage return disclosed in the patent to Pitman No. 2,258,715, dated October 14, 1941, together with devices for causing selective returns automatically incidental to the operation of the machine whereby certain stock-expressions are automatically typed;

Figure 10 is a diagrammatic representation of an arrangement of spurs for inciting progressively proper operations for the typing of the phrase "Dear Sir:", and also for automatically causing a carriage return to an intermediate return position.

Referring now more particularly to Figure 1, a carriage 10 is adapted to travel in letter feed and return direction upon front and rear tracks 11 and 12 respectively, in a manner usual in the conventional Underwood typewriter. The carriage 10 has case-shiftably supported thereon in a usual manner, a frame 13 carrying a platen 14. Said carriage tracks 11 and 12 are supported upon the main frame 15 of the machine which also supports a segment 16 whereon a full complement of the type-bars 17 are pivotally mounted for swinging movement to a common typing point, each type-bar 17 having a type-head provided with a lower-case and an upper-case type 18, 20, respectively. In the full-line position of the platen 14, see Figure 1, the lower-case types 18 will print, but when the platen is raised to the position indicated in dot-and-dash lines, the upper types 20 will print. The type bars 17 are pivoted in an arcuate array on an arcuate pivot rod 21 and each type-bar is connected at its rear to an upright operating lever 22 through a pin-and-slot connection 23, the levers 22 being pivoted at their lower ends upon a common pivot rod 24 and being guided in vertical slots of a frame bar 25 carrying said pivot rod. Extending forwardly from the various levers and articulated thereto at points 26, above the rod 24, there are coupler-links or actuators 27 normally influenced to bear upwardly against a bar 28, under the urge of tensile springs 30. These springs act in an upward and rearward direction and, therefore, tend constantly to return the associated parts 27, 22 and the type-bars to their normal positions in which the latter all lie in an arcuate array against an arcuate rest, not shown. Each of said coupler links 27 carries at its front end a toothed head 31 normally poised idly over a toothed operating shaft 32 extending crosswise of the machine and continuously power driven in the direction of the indicated arrow. It will be seen that whenever one of the actuators 27 is lowered so that its toothed head 31 is engaged with the toothed shaft 32, such actuator will be power actuated forwardly by the shaft 32, and through the lever 22 will actuate the associated type bar 17. For selectively coupling said actuators 27 with the toothed operating shaft 32, there are provided a full complement of fore-and-aft extending type-key levers 33, which are all pivoted near the rear of the machine on a rod 34, and which intermediate this rod and operating key-heads 35 have all a hook-link connection 36 with one of the actuators 27. Said hook-links are carried on their respective levers by means of pin-and-slot connections 31 and springs 38 anchored oppositely to said links and the levers provide for yieldably urged downward movement of the hook-links and associated couplers or actuators under the selective control of the type-key levers 33. This is to permit effective operation of the type-keys even though the teeth of the coupler-head and the shaft 32 may momentarily meet

edge to edge. It will be seen further that each spring 38 maintains its connected hook-link resiliently in a forward position defined by cooperation of a laterally extending lip 40 on the hook link with an upright finger 41 on the key lever. The upper or hook-end of the hook-link 36 normally overlies a laterally bent-off ear 42, in position to pull the actuator down. When upon depression of a key an actuator becomes connected to and is being drawn forwardly by the operating shaft 32, and when the type consequently approaches printing position, an inclined face 29 on the actuator engages a deflector device generally designated by the numeral 43, and will cause disengagement of the actuator from the operating shaft. The type, however, will continue to move by momentum to effect printing, whereafter the spring 30 returns the actuator to normal position, enforcing also the return of the type-bar 22 and its operating lever. Should the operator dwell on a key, a repeated power actuation of the type-bar will be frustrated by a temporary engagement of the ear 42 on the returning actuator against the hook-link 36, just above the hook face proper, the hook link 36 being temporarily yielding rearwardly until the key is released and becomes restored under the power of its return spring 49.

The machine embodies also power devices for effecting a relative case-shift between the platen and the types. To the above ends the platen-carrying frame 13 is case shaftable by a shift rail 44 which is part of a rockable structure comprising also two spaced side members 45 connected by a rod 46, said structure being rockably carried on the main frame 15 about the axis of the rod. The platen frame is guided upon the carriage 10 for vertical case-shift movements by conventional means, not shown, and the usual devices for establishing case-shift limit positions are also not shown. Referring again to Figure 1 but also to Figure 6, it will be seen that the right side member 45 of the rockable structure 47 has pivotally attached thereto and extending forwardly therefrom an elongate coupler link or actuator 48, carrying at its forward end a toothed head 50 which is similar to those on the type-action actuators 27. The toothed head 50 is normally kept out of engagement with the toothed operating shaft 32 by a spring 51, the power of latter and the tendency of the rocking frame 47 to settle biasing the actuator rearwardly to normal position. When it is desired to type in upper case the typist may depress either of two case-shift keys 52 provided at opposite ends of the keyboard. These keys consist of levers which are fixedly carried upon a transverse rock shaft 53 fulcrumed at its right end in the frame 15 and at its left end in an upstanding branch of a bracket 54 seen in Figure 2. Operation of either of the case-shift levers 52 transmits motion over a pin-and-slot connection 55 to a lever 56 being pivoted near the rear of the machine upon the pivot rod 34 and having a hook-link connection 57 with the case-shift actuator 48, said hook-link connection being a duplicate of the hook-link connection 36 heretofore described with reference to the type-bar actuating devices. When either one of the case-shift levers or keys 52 is depressed, the actuator 48 with its toothed head 50 is moved downwardly into engagement with the constantly driven operating shaft 32, with the result that a forward movement is imparted to the case-shift actuator 48 and that the platen frame is thrown to upper case position. Just before the upper case position is reached the

toothed actuator head 50 is cammed clear of the toothed shaft 32 by the engagement of the inclined face on the actuator with the deflecting device 28, but completion of the shifting movement is assured by reason of the inertia stored in the parts. So that the platen may remain in case shifted position for the full duration of the case-shift key depression, there is provided on the frame, pivotally mounted, a latch member 58 which, upon completion of the shift movement of the platen frame, drops to a position wherein a shoulder 60 thereon cooperates with a pin 61 on the actuator 48 to hold the latter in the forward position. However, as soon as the operator releases the operated case-shift key, the lever 56 will rise to normal position under the urge of a returning spring 62 and will, through a lifter 62 pivoted thereto, raise the latch 58 from the pin 61; wherefore, resultingly the actuator 48 and also the platen frame 13 will return to normal lower case position under the stored power of gravity of the platen frame and the power of the spring 51. The upper end of the lifter 62 may be guided in a slot 64 of the frame bar 25, see Figure 6, the rod 24 constituting a closure for the open side of the slot.

The carriage is normally urged to move leftwardly as seen from the front, but its letter-feed movement is governed by a letter-feed controlling mechanism comprising, an escapement device 65 normally checking an escapement wheel 66 against letter-feed rotation, said escapement wheel being supported for rotation on the frame, in the usual manner, and being geared to the carriage by means of a pinion 67 and a carriage rack 68. At the end of each type-bar printing stroke a heel 70 on the operated type bar forces the conventional universal bar 71 rearwardly to actuate the escapement 65 and thereby to cause a letter-feed movement of the carriage, the universal bar being guided at the front in the segment 16, and at the rear by spaced arms 72 of a rocker frame 69 having pivotal connections with the universal bar. The escapement 65 assumes a normal position upon the return of each operated type-bar, in readiness for a new carriage feeding operation.

Power mechanism is provided to actuate the escapement 65 responsive to the depression of a space-key 73 such as when it is desired to introduce a word space. This power mechanism comprises an actuator 74 which is operable similarly to the type-action actuators 27, and when operated actuates a mechanical train to the rocker frame 69, comprising an arm 75 having an abutting pin connection with an arm 76 fast upon a transverse rock shaft 77, which shaft has, midways of the machine, a rearwardly extending arm 78 operatively associated with a forwardly and downwardly extending branch 79 of the rocker frame 69. The arm 75 is pivoted on the rod 24 in the same manner in which the type action operating arms 22 are pivoted and, similarly to the other actuators, the actuator 74 is normally maintained in contact with the bar 28 under the influence of a spring 81 so that its toothed head 80 is normally clear of the operating shaft 32, the spring 81 being also effective to return this actuator and connected mechanism to normal position. The actuator 74 is lowered for operation by the constantly operating shaft 32 through a hook-link 82 supported upon a lever 83 which is operable through a leftmost one of three supporting arms 85 of the space key 73, over a pin and slot connection 84. The details of the struc-

ture of the hook-link 82 are similar to those of the hook-links 36 heretofore described in connection with the type actions, so that there is no need for further elucidation thereof. The lever 83 is constantly under the influence of a return spring, not shown, and the arms 85 supporting the space key 73 constitute together with a shaft 86 a unitary structure pivoting about the shaft axis, the shaft being pivotally mounted in the same manner as shaft 53.

Automatic stock-expression typing

Upon the underside of the machine, there are a plurality of selectively rotatable operators or rotors 90, each provided with means that represent a particular sequence of operation for the types and the word spacing mechanism, in correspondence with a certain stock-expression to be selectable for automatic typing. The rotors or operators, three of which are provided in the shown embodiment of the invention, are in the form of square shafts 92 being substantially coextensive with the width of the machine and having reduced fulcrum ends extending oppositely into vertically disposed bracket plates 93 fastened by screws, not shown, against the inner sides of the opposite side walls of the machine frame 15. Extending downwardly and rearwardly underneath the rotors 90 from the various type-key levers 33 and the spacing lever 83 are reaches 94 which have prongs 95 directly underneath and pointing towards the three rotors. At appropriate locations along the square shafts 92 there are collars 99 which have each one or more radially projecting tappets or spurs 96, these spurs on the several rotors being relatively arranged to act upon rotation of the rotor on the underlying prongs 95 of the various levers 33 and 83 in such order as to bring about a particular sequence of operation of the typing levers 33 and the spacing levers 83 resulting in the typing of a certain stock-expression.

Stating it differently, rotation of any rotor causes the associated prongs to read out and translate the sequence representations into type-key operations.

Additional to the collars 99 the rotors may have collars 99a and 99b, respectively having spurs or tappets 96a and 96b for respectively calling into being automatic case shifting operations and automatic carriage returning operations.

The several rotors shown in the illustrated embodiment of the invention are equipped, the foremost one with spurs for typing the phrase "Dear Sir:", and those successively more rearward, with spurs for typing "Yours truly," and "Very truly yours.". A diagrammatic representation of the arrangement of the spurs on the foremost rotor is given in Figure 10 in flattened aspect. It will be noted that the spurs for initiating the appropriate operations for typing "Dear Sir:" are shown in this view, top to bottom, in the order of their timed arrangement around the rotor, the significance of which arrangement will become more clear hereinafter.

The several rotors 90 are adapted to be called into use individually by selective operation of three selector keys 97, situated in convenient reach of the operator, at the right side of the machine. The topmost key 97 calls the rearmost rotor into operation and the successively lower keys call into operation the successively more forwardly disposed rotors. Each rotor-shaft 92 has turnably situated thereon, on a round shaft part 92a, a gear 98 and the several gears 98 on the

neighboring rotor shafts are in constant mesh with each other and constantly, but normally idly driven by a gear train 100, 101, 102, 103, see Figures 1 and 2, connecting the rearmost gear 98 with the aforementioned toothed operating shaft 32, it being noted that the gear 98 upon the middle rotor, as viewed in Figure 1, rotates clockwise whereas the gears 98 on the other two rotors rotate counterclockwise. Each of the several gears 98 is axially maintained in position by a shaft shoulder 92b and a retainer screw 119 reaching into a circumferential groove in the shaft, see Figure 7.

For detenting the rotors in their normal positions seen in Figures 1, 2 8, 9, each rotor shaft 92 has near its left end, see Figures 2 and 9, a collar 104 provided with a detent notch 105 and upon each of these an individual detent finger 106 resiliently bears down under the tension of a spring 107.

Devices are provided whereby upon operation of any one of the selector keys 97 the appropriate rotor 90 is clutched to the gear 98 thereon for a single revolution, the position of the rotor and the spurs after each revolution being such that typing results promptly at the very start of each revolution. Drawing now attention to Figures 2 and 7, it will be seen that each rotor shaft 92 carries axially slidable thereon a clutch member 108 having a clutch cone 109 for engagement with a cone-shaped clutch cavity 110 in a hub of the axially adjacent gear 98. The clutch member 108 is slidably splined to the rotor shaft as at 111 and when it is shifted leftwardly to engage its cone 109 with the counterpart 110 on the gear 98, the gear will drive the rotor. Whenever it is desired to print one of the stock-expressions, the operator merely pushes the proper selective key 97 rearwardly, thereby causing a key-slide 112 to impart a turning movement to a vertical shaft 113, the latter for this purpose having an arm 114 wherewith the key-slide has an articulation 115. Said turning movement of shaft 113 is transmitted to a clutch operating member 116 having a vertical pin engaging a circumferential groove 117 in the clutch member 108. In turning any one of the shafts 113 for closure of the associated clutch, there is swung in a forward direction a horizontal arm 118, see particularly Figures 2 and 8, such arm having a hub 120 for fastening it to the shaft 113. Overlying the left end of each one of the several arms 118 is a latching lever 121 and these levers are pivoted in laterally adjacent relation upon a common, frame-supported pivot stud 122, whereon incidentally also the gears 101 and 102 rotate, and are resiliently urged down upon the several arms 118, by means of springs 123. Said levers 121 permit normally unobstructed forward swinging of the said arms 118 and when any particular rotor clutch has been closed through selective operation of its associated key, one of the levers 121 will present a shoulder 124 directly in back of the operated arm 118, thus retaining it and the key in operated position even though the operator may remove the finger from the key. Therefore, obviously, the operator need only tap the keys 97, inasmuch as in each case the appropriate clutch thereafter is held closed. Any rotor for which the control key has been operated cycles one full revolution, at the end of which the effective latch lever 121 will be given an upward displacement by engagement of a rotor-carried cam tooth 126 with a cam face 127 on the lever, resulting in the freeing of the arm 118 from the shoulder 124, and in the return of

the shaft 113 and the key to normal, open-clutch position, under the urge of a spring 133 attached to an arm 134 integral with the arm 114. Said cam teeth 126 are provided on collars 128 fastened to the rotor shafts. To assure firm engagement of the clutch 109, 110, there is provided, coiled around the arm hub 120, a torque spring 130 which so connects the arm 118 with the clutch operating member 116 that the former resiliently actuates the latter, the condition being such that the clutch becomes closed before the arm 118 is fully operated and locked by the shoulder 124; it being noted here that the clutch operating member 116 has a bail-like portion 132 by means of which it is pivotally carried on the shaft 113 in an axial location defined by the arm hub 120. The normal relation between the clutch operating member 116 and the arm 118 is established by engagement of a finger 131 on the arm 118 with said bail portion 132.

Certain phrases or stock-expressions call for the typing of one or more upper-case characters. Accordingly, the rotors 90 may have each a collar 99a with one or more case-shift signifying or controlling tappets or spurs 96a located in properly timed relations with respect to the other spurs. These case-shift controlling spurs 96a act upon prongs 95a of which there is one underneath each of said collars 99a and all of which are part of a lever 136, best seen in Figure 6. The lever 136 is pivoted in the same manner as the levers 33 and 83 and has at its front a pin and slot connection 137 with the left case-shift key 52. Consequently, whenever one of the case-shift spurs 96a wipes over one of the prongs 95a, the lever 136 will be cammed downwardly and through the connection 137 will operate the case-shift keys 52, resulting in the depression of the lever 56 and the connection of case-shift actuator 48 with the toothed shaft 32, and ensuingly in a case-shift of the platen by power to upper case. Inasmuch as the case-shifting operation must be completed before the actual imprint takes place, and since the case shift must be maintained until the imprint has been made, the case-shift spurs 96a have rises 138 which are timed in advance of the rises on those character spurs in behalf of which they are intended to act, and have, furthermore dwells 139 to sustain the case-shift for an appropriate period, it being recalled here that the platen frame remains locked in upper case by the latch 58 as long as the case-shift key 52 remains operated. As soon as an operating case-shift spur 96a passes or clears a prong, the lever 136 will be restored by its spring 140, wherefore also the lever 56 is restored, thereby causing the release of case-shift latch 58 by the lifter 63 and consequent restoration of the platen.

If a stock-expression calls for the typing of several succeeding characters in upper case, the dwell 139 is extended to maintain the machine case-shifted while typing of all such characters is effected. In the event the phrase consists entirely of upper case characters, the dwell 139 may be extending almost fully around as shown in Figure 5a, leaving substantially a notch large enough only to provide a clearance for the underlying prong when the rotor is in normal position, meaning, that the case-shift latch 58 remains active while the entire expression is being automatically typed.

Automatic carriage return

Certain phrases or expressions, as, for example, salutations, call for the return of the carriage to

a specific position after typing thereof has been effected. For instance after typing "Dear Sir:", the next line is usually indented, that is the return of the carriage is to an intermediate position. On the other hand, writing of such phrases as "Yours truly," require a full return of the carriage. In appreciation of this, the invention provides for automatically initiated carriage returns to a number of specific predetermined positions, in direct dependence of the particular phrase or stock printing operation called into being by the control keys 97. Directing now attention to Figure 9 there is shown a portion of the selective carriage return mechanism disclosed in the patent to Pitman No. 2,258,715 of October 14, 1941, together with devices whereby automatic carriage returns will follow automatic typing of stock expressions, whenever this is desired.

So far as it is thought helpful to an understanding of the invention, certain features of the carriage return of said patent will now be described. The mechanism of said patent, provides for the return of the carriage by power to an extreme or rightmost returned position when a carriage return key CR is depressed. Upon depression of another return key RI, the carriage will be power-returned to a right intermediate position, whereas if a key LI is operated, there will follow a power-return to a left intermediate position, such latter position defining the shortest return. The three keys CR, LI, and RI are mounted respectively on key levers 141, 142, 143 and are shown disposed at the left end of the usual keyboard. Depression of any one of said return keys rocks its associated lever counterclockwise of Figure 9 about a common fulcrum 144 in the framework of the machine. Each of the said carriage return key levers has an upright arm 145 terminating in a cam end at its top. The several cam ends 145 normally stand, side by side, behind a broad pawl nose 146 of a piece 147 pivotally carried on the forward end of a link 148, the latter being part of a carriage return clutch closing mechanism fully disclosed in the aforesaid patent to Pitman. Said link 148 is normally held in a forward position by reason of a shoulder 151 thereof engaging a lug 152, but upon depression of any one of said carriage return keys the link 148 will be cammed upwardly by one of the arms 145, sufficiently to free the shoulder 151 from the lock 152. Resultingly, the link 148 is spring-moved rearwardly to close a carriage return clutch, not shown, in the manner fully disclosed in the said patent to Pitman. The machine of said patent embodies three carriage return stops, not shown, one of which is an extreme return stop normally in position to terminate a return called into being by depression of the key CR. The other two stops are a right and a left intermediate stop respectively adapted to be called into use by the depression of key RI, and the key LI, through differing extent setting movements impartable to an upright link 153 from the key levers 142, 143, by the medium of a bell crank 154, said bell crank being pivoted on the stud 144 and having a pin 155 lying in front of only those upright arms 145 which belong to the keys 142, 143. More specifically, the key 143 when depressed, lifts the link 153 through said bell crank 154 a single step, thereby to select the right intermediate stop, and the key 142 when operated, lifts the link two steps, thereby to select the left intermediate stop, a latch mechanism 156 being provided to detain

the link 153 in either of the two lifted positions. It will thus be seen that the carriage is returnable by motor power in response to the depression of the keys CR, LI, RI, respectively to a full return position, a left intermediate position, or a right intermediate position, it being understood that at the termination of any return the mechanism becomes normalized, as fully disclosed in said patent to Pitman. Attention is also directed to the fact that said carriage return stops are presentable by hand to different carriage return terminating positions and further that incidental to each power-operated carriage return there occurs automatically a line spacing operation of the platen to present a new typing line opposite the typing point.

The machine of the present invention provides for selective operation of said carriage return keys automatically as an incident to automatic 20 typing of stock-expressions, and directing now particular attention to Figure 2, in addition to Figure 9, it will be seen that those up-right arms 145 belonging to the keys CR and RI have links 160 in abutting relation directly in back thereof. Each of these links 160 is guided near its front end in a perforation in a usual key-lever comb-plate 159 and is power operable by an actuator 161 through an upright lever 162, these actuators being normally clear of the toothed power shaft 30 32 but being transitorily connectable therewith by operation of a lever 163 having a hook-link connection 164 for drawing the actuator 161 into motion receiving engagement with said shaft. Said levers 163 extend underneath the rotors 35 and have prongs 95b thereon for actuation by carriage return spurs 96b provided on collars 99b fastened on the rotor shafts. In the particular embodiment of the invention shown, the front rotor has spurs arranged for typing "Dear Sir:" 40 and since such phrase is ordinarily to be followed by a return of the carriage to a paragraph in position, this rotor is provided with a collar and spur located to operate the left one of two levers 163, this lever being in control of the power operating train 161, 162, 160 leading up to the key lever arm 145 of the carriage return key RI. Since after the typing of such phrases as "Yours truly," and "Very truly yours," it is usually in order to return the carriage to an extreme return 50 position, the two other rotors have each a collar with a spur 96b thereon for the calling into operation that power train 161, 162, 160 which leads to the key lever arm 145 of the key CR. The spurs 96b, of course, are arranged to act on the associated prongs 95b just after the last character of the phrase has been printed. A yielding connection 169 is provided between the levers 162 and the links. This connection yields after full operation of the arm 145 by the link 160, the actuator 161 being given an excess amount of motion to make close adjustment of throw unnecessary.

Typing of a short phrase such as "Dear Sir:" 65 may not advance the carriage far enough so it may be returned thereafter to the desired paragraphing position, in which case, as illustrated in Figures 5 and 10 a few extra carriage spacing spurs may be provided to succeed the last character typed, the extra spurs being directly preceding a carriage return spur 96b. Obviously every spur-initiated carriage return results in a line spacing operation, in the same manner as the key initiated carriage return.

The key-slides 112 are guided at the front in slots 165 provided upon an inwardly reaching rib

of the right side wall of the machine, such slots being closed at the left by a fixed plate 168. At the rear the slides are guided in open slots 168 of a block 167 carrying a rear plate 170 closing off the slots 168 at the left sides, said plate having anchorages 171 for the several key restoring springs 133. Tabs 172 extending laterally from the rear end of the key-slides establish normally in cooperation with the block 161 the normal positions of the keys 97 and connected mechanism. The extent of operation of the several keys is limited by other tabs 173 adapted to engage the front side of the block 167. A shelf-like bracket 174 serves to support pivotally the shafts 113 at their upper region and at the rear this same shaft has fastened thereto in an upright position the said block 167. A horizontal shelf of the right hand bracket plate 93 supports pivotally the lower ends of the shafts 113.

The invention provides that no more than one selector key is operable at a time and since the key when once operated will be detained in operated position by cooperation of the latch shoulder 124 with the arm 118, it follows that one phrase printing operation cannot be initiated while another is still in progress. To the above end the key-slides have locking tabs 175, any one of which when a key is operated will crowd round-ended lock members 176 obstructively in front of the other tabs, said lock members 176 being accommodated for vertical displacement in a vertical perforation of the block 167 being closed off at opposite ends by screws 177, it being at no time possible to advance more than one of the said tabs to operated position. It follows, therefore, that the keys 97 are incapacitated whenever a stock-expression is being automatically typed.

The carriage return mechanism is intermittently driven by an electric motor, not shown, which motor constantly drives the toothed shaft 32 by means of a transmission including a belt and pulley drive 178 shown in Figure 2.

The various spur-carrying collars are fitted non-rotatively on their shaft 92 and are clamped by screws 179 in their proper locations.

Whatever expression selecting key 97 may be operated, the machine will promptly begin to translate the functional representations of the spurs into character typing and other operations, and in the fastest practical succession, so that typing by the conventional type keys may be resumed at the earliest possible moment, which may be even before the operated rotor has returned to its normal position. The spurs and co-operating prongs are shaped to allow expeditious return of the prong-bearing levers to normal positions, ready for renewed operations by succeeding spurs. After the representations have been translated there follows a prompt restoration of the operated rotor, following which the representations are posed for prompt successive transcriptive action.

Wherever a stock-expression contains a space followed by an upper case character, as for example in the phrase "Dear Sir:", the controlling space spur and the case-shift spur may commence to act simultaneously. However, the case-shift spur is provided with a long dwell for sustaining the case-shift until the spacing spur and the character spur have successively been active. See schematic representation given in Figure 10.

Variations may be resorted to within the scope of the invention, and portions of improvement may be used without others.

Having thus described my invention, I claim:

1. In a typewriting machine, the combination with a series of types which are selectively actuatable to a common typing point, of a power-operating-member common to all said types, a series of normally idle type-actuators disposed laterally of each other in the machine, each actuator connectible transitorily with said power-operating-member for individual operation thereby, and each actuator, when so connected, being effective to actuate a particular one of said types to said typing point, means including a type-key, individual to each actuator and disposed laterally of each other in the machine, each operable to connect transitorily for a single action the associated type-actuator with said power-operating-member for a single typing operation, a plurality of sets of camming tappets for operating control of said individual connecting means, the tappets of the different sets being disposed relatively to one another to comprise together different specific programs of operating control for said individual connecting means in accordance with different stock-expressions to be typed, mechanical means to translate the relative disposition of the tappets of said sets into the programs of operation of said individual connecting means which they comprise, said translating means including means normally posed for immediate relative read-out movement with respect to any one of the several sets of tappets, normally ineffective power means selectively conditionable to impart relative read-out movements between any one of different sets of tappets and said posed means at controlled speed, and thereafter to effect prompt relative restoration therebetween, and selectively operable key-means to condition selectively said power means to impart any one of said relative read-out movements.
2. In a typewriting machine, the combination with a series of types which are selectively actuatable to a common typing point, of a power-operating-member common to all said types, a series of normally idle type-actuators disposed laterally of each other in the machine, each actuator connectible transitorily with said power-operating-member for individual operation thereby, and each actuator, when operated, being effective to actuate a particular one of said types to said typing point, a plurality of elements extending parallel to the direction in which said actuators are disposed laterally of each other, said elements being severally formed to control connection of the said actuators with said power-operating-member in accordance with appropriate connecting programs called for, for typing certain stock-expressions, each of said elements being normally stationary, but operable for promptly bringing into effect the program of actuator connections which its particular form controls, means to power-operate said elements selectively and at sufficiently slow speed to cause successive power operation of the desired types by said actuators in accordance with the said actuator connecting programs, said power-operating means including, a continuously running motor and normally inoperative selective driving means for said elements to drive them selectively at controlled speed individually, and including also provision to cause prompt return of the said elements following the typing of the stock-expression, and key-means to render said driving means selectively operative with respect to any one of said elements followed by a restoration thereof.
3. In a typewriting machine, the combination

with a series of types which are selectively actuatable to a common typing point, of a power-operating-member common to all said types, a series of normally idle type-actuators disposed laterally of each other in the machine, each actuator connectible transitorily with said power-operating-member for individual operation thereby, and each actuator, when operated, being effective to actuate a particular one of said types to said typing point, means individual to said actuators for connecting them for single operations by said power-operating-member, said connecting means being disposed laterally of each other in the machine, a plurality of elements extending parallel to the direction in which said connecting means are disposed laterally of each other, each of said elements having a series of camming tappets in relative locations thereon to represent together a distinct program of connecting sequences for said actuators in accordance with a specific stock-expression to be typed, each element, with its tappets, being normally stationary, but operable for substantially immediate action of its set of camming tappets on said connecting means to operate on the latter in accordance with the connecting sequences represented by its set of tappets, means to power-operate said elements selectively at controlled speed for seriatim action of the tappets on said connecting means, followed by a prompt automatic restoration of the operated elements to normal position, said power means including normally inoperative individual driving connections for said elements, and key-means to render said driving connections selectively operative for an operation of any desired one of said elements followed by a said restoration thereof.

4. In a typewriting machine, the combination with a series of types which are selectively actuatable to a common typing point, of a power-operating-member common to all said types, a series of normally idle type-actuators disposed laterally of each other in the machine, each actuator connectible transitorily with said power-operating-member for individual operation thereby, and each actuator, when operated, being effective to actuate a particular one of said types to said typing point, means individual to said actuators for connecting them to said operating members for single operations thereby, said connecting means being disposed laterally of each other in the machine, a plurality of rotors disposed in parallel to the direction in which said actuators are disposed laterally to each other, each rotor being normally stationary and being arranged and formed for cooperation with said connecting means to cause the latter in the course of one rotor revolution to be operated in accordance with a program suited for typing a certain stock-expression, normally inoperative power means to impart single revolutions to any one of said rotors at sufficiently slow speed for the types to make consecutive imprints, said rotors being normally positioned for promptly bringing into effect their programs of operations for said connecting means, and special keys selectively operable to cause said power means to impart a single revolution to any one rotor.

5. In a typewriting machine, the combination with series of types which are selectively actuatable to a common typing point, of a power-operating-member common to all said types, a series of normally idle type-actuators disposed laterally of each other in the machine, each actuator connectible transitorily with said power-

operating-member for individual operation thereby, and each actuator, when operated, being effective to actuate a particular one of said types to said typing point, a plurality of elements extending parallel to the direction in which said connecting means are disposed laterally of each other, said elements being severally formed to control connection of said actuators in accordance with appropriate connecting programs called for, for typing certain stock-expressions, each of said elements being normally stationary, but operable for promptly bringing into effect the program of operation which its particular form controls, means to power-operate said elements selectively and at sufficiently slow speed to cause successive power-operation of the desired types by said actuators in accordance with the said programs of operation, said power-operating means including, a continuously running motor, and normally inoperative selective driving means for said elements, and including also provision for prompt return of said elements following the typing of the stock-expression, a special key associated with each one of said elements, means responsive to operation of any one of said special keys to render the selective driving means operative upon the element that is associated with the operated special key, and responsive also to the operation of any special key to incapacitate the other special keys for the interim in which typing operations result, said responsive means including means, operative independently of the early release of the operated special key by the operator, to maintain the other special keys incapacitated so long as typing operations are being called into effect by the operated element.

6. In a typewriting machine, the combination with a series of types which are selectively actuatable to a common typing point, of a power-operating-member common to all said types, a series of normally idle type-actuators disposed laterally of each other in the machine, each actuator connectible transitorily with said power-operating member for individual operation thereby, and each actuator, when operated, being effective to actuate a particular one of said types to said typing point, means individual to said actuators for connecting them to said operating members for single operations thereby, said connecting means being disposed laterally of each other in the machine, a plurality of rotors disposed in parallel to the direction in which said actuators are disposed laterally to each other, each rotor being normally stationary and being arranged and formed for cooperation with said connecting means to cause the latter, in the course of one rotor revolution, to be operated in accordance with a program suited for typing a certain stock-expression, normally inoperative power means to impart single revolutions to any one of said rotors at sufficiently slow speed for the types to make consecutive imprints, said rotors being normally positioned for promptly bringing into effect their programs of operations for said connecting means, a special key associated with each one of said rotors, means responsive to operation of any one of said special keys to cause said power means to impart a revolution to the rotor which is associated with the operated special key, and responsive further to operation of any one of said special keys to incapacitate the other said special keys in the interim the typing operations resulting from the revolution imparted to the rotor are being automatically effected, said responsive means including rotor-controlled means,

operative independently of an early release of the operated special key by the operator, to maintain the other special keys incapacitated so long as typing operations are being called into effect by rotor rotation.

7. In a typewriting machine, the combination with lower and upper-case sets of types, of a body shiftably positionable in the machine in either a lower or an upper-case position for rendering respectively said lower-case or said upper-case set of types selectively actuatable for typing at a common typing point, a series of normally idle type-actuators disposed laterally of each other in the machine, a power-operating-member common to all said actuators, said type-actuators being normally idle but being each transitorily connectible to said power-operating-member to actuate, depending on the case-position of said body, either an upper or a lower-case type to the typing point, means including a plurality of camming tappets disposed with respect to each other for connecting control of said actuators in accordance with a predetermined program of successive operation for said actuators, a part movable from and to a normal position, power means responsive to movement of said parts from said normal position to move said case-shift body from said lower-case to said upper-case position, and responsive to movement of said part to said normal position to move said body from said upper to said lower-case position, said power means including electric-motor-actuated-means to move said body at least from one to the other of said two case-positions, and cam-means comprising a rise and a drop-off with an intervening dwell, said rise and drop-off being to control opposite movement of said part respectively to the said two case-positions, and being disposed for effecting such control at certain spaced points in said predetermined program of operation for said actuators, normally ineffective mechanical means to translate the relative disposition of said tappets into actuator connections in accordance with the said program, and also to translate the disposition of said rise and the said drop-off into opposite movements of said part at said spaced points in said program, said translating means including, means adapted for relative read-out movement with respect to said tappets and said cam-means, and including also power-means conditionable to impart said relative read-out movement at controlled speed, and means to render said mechanical translating means effective.

8. In a typewriting machine, the combination with lower and upper-case sets of types, of a

body shiftably positionable in the machine in either a lower or an upper-case position for rendering respectively said lower-case or said upper-case set of types selectively actuatable for typing at a common typing point, a series of normally idle type-actuators disposed laterally of each other in the machine, a power-operating-member common to all said actuators, said type-actuators being normally idle but being each transitorily connectible to said power-operating-member to actuate, depending on the case-position of said body, either an upper or a lower-case type to the typing point, a plurality of elements extending parallel to the direction in which said connecting means are disposed laterally of each other, each of said elements having a series of camming tappets in relative locations thereon to represent together a distinct program of connecting sequences for said actuators in accordance with a specific stock-expression to be typed, a part movable from and to a normal position, power means responsive to movement of said part from said normal position to move said shift body from said lower to said upper-case position, and responsive to movement of said part to said normal position to move said body from said upper to said lower-case position, said power means including electric-motor-actuated-means to move said body at least from one to the other of said two case-positions, cam-means on said elements, comprising rises and drop-offs with intervening operatively inactive zones, said rises and drop-offs being disposed for controlling movement of said part respectively to and from operated position to cause case-shift of said body to upper-case position in advance of certain actuator connections effected under control of said camming tappets, said inactive zones being provided to maintain case-shift of said body to upper-case position until an appropriate one or more typing impressions have been effected by one or more successively connected actuators, said elements being normally stationary, but individually operable to bring into effect substantially immediately the program of actuator-connections represented by the sets of tappets thereon, and also to bring into effect the case shifts represented by said rises and drop-offs, means to power-operate said elements selectively at controlled speed for the assigned functions of their sets of tappets and cam-means, followed by prompt automatic restoration of the operated element to normal position, and means to render said power operating means selectively operative with respect to the said different elements.

ALFRED G. F. KUROWSKI.
